UNITED STATES PATENT OFFICE.

GEORGE E. BOWERS, OF FITCHBURG, MASSACHUSETTS.

STRIKING MECHANISM FOR ELECTRIC BELLS.

SPECIFICATION forming part of Letters Patent No. 252,175, dated January 10, 1882.

Application filed September 8, 1881. (Model.)

To all whom it may concern:

Be it known that I, GEORGE E. BOWERS, of Fitchburg, in the county of Worcester and State of Massachusetts, have invented a new and useful Improvement in Striking Mechanism for Electric Bells, of which the following is a full, clear, and exact specification.

My improved mechanism provides for a long stroke of the hammer, movement of the hammer always in one direction, compactness of construction, and a positive stop in a manner requiring but slight force to release the striking mechanism.

The invention consists in a hammer in the form of a segment of a ring, hung on a shaft that is revolved by a weight or spring and released by movement of the armature of an electro-magnet, as hereinafter described and claimed.

Reference is to be had to the accompanying drawings, forming part of this specification, in which similar letters of reference indicate corresponding parts in all the figures.

In the drawings, Figure 1 is a side elevation of an electric gong embodying my invention. Fig. 2 is a front view of the same. Fig. 3 is a detail side view of the hammer and its shaft, in section, on line *x x* of Fig. 2. Fig. 4 is an edge view of the hammer, and Fig. 5 is a detail section on line *y y* of Fig. 2.

The bell and mechanism are supported by a bracket consisting of a ring, *A*, and arm *B*, to which the ring is attached.

C is the gong, suspended from the upper side of ring *A*.

D is the magnet, hung on arm *B*.

a is the pivoted armature-lever, which draws downward from the poles of the magnet by its weight, assisted by a spring, if required.

b is a stop for the armature.

c is a shaft carrying a winding-drum, *d*, from which a weight, *e*, is suspended by a cord that passes over a friction-roller, *f*.

g is the hammer-shaft, provided with a fast pinion, *h*, meshing with a gear-wheel, *u*, on shaft *c*.

E is the hammer, hung loosely by an arm, *i*, on the shaft *g*. On the shaft is a ratchet-wheel, *k*, that is engaged by a pawl, *l*, hung

on the hammer-arm *i*, so that the hammer is carried by the shaft when the shaft is turned by the weight *e*.

The hammer *E* is the segment of a ring, pivoted at one end by a pin, *m*, to the arm *i*, so that its outer end is free to swing in and out a distance limited by a stop-pin, *n*, that projects through a hole in a tail of the hammer. A spring, *o*, from the pawl *l* to the hammer, serves to retain the hammer end inward, and also as a spring to retain the pawl in place. The hammer-arm *i* has an extension, *p*, curved in the same arc as the hammer, and forming a tail to the hammer. On the end of this tail portion *p* is a cross-pin, *q*, and on the armature-lever *a* are two lugs or projections, *r r*, placed one for contact with the end of pin *q* when the armature is down, and the other for contact therewith when the armature is raised in contact with the magnet. This contact with the lugs *r* by pin *q* arrests the hammer and prevents its being revolved by the weight.

The location of the curved hammer is below the edge of the bell, at one side, in such position that the hammer strikes at about the end of its upward movement. As the shaft *g* carries the hammer, the centrifugal force acting on the long arm overcomes the resistance of the spring acting against the short arm and throws the end of long arm out, so as to come in contact with the bell, which checks it and allows the spring on short arm to force the end of long arm inward, when it passes the bell and moves on until arrested by the pin *q* and upper lug *r*. When the armature is raised by closure of the circuit to the magnet the upper lug *r* is raised above pin *q* and the lower lug *r* brought behind the pin. When the armature drops by breakage of the circuit the lower lug *r* is carried down, and the pin *q* being entirely released, the hammer revolves, and the blow is struck at completion of the revolution.

It will be seen that the movement of the hammer is continuous in one direction, so that there is no loss of power. The hammer has a long stroke and moves with increasing momentum. The position of the hammer at rest is such that it partially balances the driving power, so that but a slight magnetic force

is required to release the hammer; and, further, the stop action is positive and endwise of the armature.

A pawl, *s*, on the bell-frame engages the 5 notched hub *t* on the hammer-arm *i*, and serves to retain the hammer in position, if at any time the impelling force is relieved.

Having thus fully described my invention, I claim as new and desire to secure by Letters 10 Patent—

1. The combination, with the shaft *g*, carrying ratchet-wheel *k*, of the hammer *E*, hung loosely on arm *i*, projecting from shaft *g*, the stop-pin *n*, passing through a cross-slot or hole 15 in the hammer-tail *p*, the spring *o*, and the pawl *l*, pivoted on said arm *i*, whereby the ham-

mer is adapted to be operated with respect to the bell as described.

2. The combination of segment-hammer *E*, propelling-shaft *g*, arm *i*, tail-piece *p*, provided 20 with pin *q*, and the armature-lever *a*, provided with lugs *r*, substantially as shown and described.

3. The combination of the impelling-shaft *g*, ratchet *k*, pawl *l*, arm *i*, pivoted hammer *E*, 25 and stop-lever *a*, substantially as shown and described, for operation as set forth.

GEORGE E. BOWERS.
